Des. 189,660
Patented Jan. 31, 1961

189,660

MACARONI

Paul A. Vermylen, 15 Ramapo Lane, Hillsdale, N.J.

Filed Sept. 19, 1960, Ser. No. 62,192

Term of patent 14 years

(Cl. D8—1)

Fig. 1.

Fig. 2

Fig. 3.

Fig. 1 is a perspective view of one side of a piece of macaroni embodying my new design;

Fig. 2 is a perspective view of the other side of the same piece of macaroni; and

Fig. 3 is a section taken along the line 3—3 of Fig. 1.
I claim:

The ornamental design for macaroni, as shown.
